Application December 22, 1934, Serial No. 758,746

8 Claims. (Cl. 101—93)

This invention relates to tabulating machines and more particularly to improvements in the printing mechanisms therefor.

Tabulating machines as presently developed are provided with printing mechanism whereby numerals represented by index point perforations may be indicated by printing upon a record strip and in addition thereto such printing mechanism is also employed to represent the result of some computation such as a total of a series of items.

The principal object of the present invention is to provide a printing mechanism for tabulating machines of new and improved construction through which the efficiency and general operation of the machine will be improved.

As presently constructed, the printing mechanism of a tabulating machine of the so-called Hollerith type is provided with seventy individual type bars mounted for vertical reciprocation and moved upwardly under control of springs connected between the type bars and an invariably reciprocating cross-head. During the upward movement of the type bars, stopping pawls may be tripped into engagement therewith to interrupt their upward movement at different times whereupon the driving springs are extended as the invariably reciprocating cross-head continues its upward movement, thus imposing an additional load upon the mechanism which drives the cross-head. This added spring tension, in addition to the weight of the type bars, is a deciding factor in limiting the speed of operation of the machine in general. It is, therefore, one of the objects of the invention to re-organize the type bar operating mechanism so that the moving mass may be considerably reduced and the addition of the usual spring tension eliminated so that a higher operating speed may be obtained.

In carrying out the invention, a plurality of columns of type elements are integrally associated with a reciprocating frame which moves all the columns of type elements past printing position concurrently. A printing hammer is provided for each column of type elements and as the elements move past printing position, the tripping of a hammer will cause the latter to strike one of the elements to take an impression therefrom without interrupting the movement of the type carrier. In this manner an impression is taken "in flight" and printing is effected at the moment of selection, which moment will vary in accordance with the value of the character selected for printing.

Heretofore in tabulating machines, all the type bars have been positioned and printing ef-

fected by the common hammer which strikes all selected type at one time. This action has required a sufficiently sturdy mechanism to print from a large number of type bars. With the present arrangement, the individual hammers 5 separately tripped may be considerably lighter in construction and the heavy blow at a definite point of time in the cycle of the machine has been obviated.

Various other objects and advantages of the 10 invention will be obvious from the following particular description of one form of mechanism embodying the invention or from an inspection of the accompanying drawings; and the invention also constitutes certain new and novel features 15 of construction and combination of parts hereinafter set forth and claimed.

In the drawings:

Fig. 1 is a central section of the improved form 20 of printing mechanism.

Fig. 2 is a section taken along lines 2—2 of Fig. 1.

Fig. 3 is a section looking in the same direction as Fig. 2, taken on lines 3—3 of Fig. 1.

Fig. 4 is a detail section on lines 4—4 of Fig. 1, 25 showing the zero printing control connections, and

Fig. 5 is a detail of parts shown in Fig. 1 in position.

Fig. 6 is a position view of parts in Fig. 1 30 shown at an enlarged scale.

Fig. 7 is a detail showing the manner of supporting the type heads.

Referring now to Figs. 1 and 3, a plurality of type element holders 10 are separately mounted 35 in a cross-head which includes side members 11 and a slotted cross member 12 provided with slots 13 within which are secured members 14. Member 14 has its vertical edges bevelled and has also riveted thereto a cross-piece 15 (see Fig. 7) thus 40 forming a pair of parallel vertical slots of triangular cross section into which the lower end of the type holder 10 is adapted to slide. Extending across the tops of holders 10 is a U-shaped bar 16 secured to the side members 11 as 45 by thumb screws 17. Removal of thumb screws 17 will permit bar 16 to be removed from across the tops of the holders 10 which latter may then be separately lifted out of position within the frame for replacement or interchange. With this 50 arrangement, all positions across the frame may be provided with holders 10 or a lesser number may be placed in position according to requirements. Each holder is provided with ten spring- 55.

pressed type plungers 18, there being one for each of the digits and zero.

The member 12 is provided with a bearing 19 at each end which is secured to a vertical rod 20 whose upper extremity is guided in bearing 21. As the rod 20 is reciprocated vertically in the manner to be explained, the type plungers 18 will successively pass printing position opposite platen 22 in the order 9, 8, 7, etc. in synchronism 10 with the correspondingly numbered index point positions of the record cards as the latter move in transit past the analyzing brushes LB in the card feeding and analyzing section of the machine. The lower end of rod 20 is guided in a 15 fixed bearing 23 directly above which there is secured to the shaft a member 24 which supports a pair of cam follower rollers 25 and 26 which cooperate with a pair of complementary cams 27 secured upon a shaft 28. Shaft 28 also carries a 20 gear 29 which, through idlers 30 is driven from a gear 31 mounted upon the so-called listing shaft 32 of the tabulating machine. This shaft makes one revolution for each cycle of the machine during which, through the mechanism traced, the frame 11, 12 and type holders 10 will be moved 25 upwardly and then down again.

Slidably supported on rods 20 is a secondary frame 33 which is provided with a roller 34 in co-operation with a cam 35 also carried on shaft 28. 30 A spring 36 secured at one end to the frame and at the lower end to bearing 23 tends to urge the frame downwardly and serves to hold roller 34 in engagement with a plurality of rises 37 numbered 9 to 1, which, as they successively cooperate with 35 roller 34, cause a succession of reciprocations of the frame 33 which are timed so that each upward stroke occurs as the correspondingly numbered type element is passing through printing position.

The rise 37 in the zero position of the cam is 40 higher than that in the other positions (see Fig. 6) and will cause a somewhat higher movement of the frame as the zero type element passes through printing position. This additional upward movement is utilized to control the printing of zeros to 45 the right of significant figures in a manner to be set forth hereinafter.

Carried by and pivoted upon frame 33 are latches 38 whose left ends are urged by springs 39 into latching engagement with a hook 40 which 50 forms an extension of a member 41 which latter is pivoted upon fixed rod 42. Member 41 has connection with a spring 43 by means of a link and roller device 44 which cooperates with an arm 45 extending from member 41 which is provided 55 with recesses 46 in which the link and roller device may engage. A U-shaped cross member 48 straddles the lower extremities of the link and roller connections 44 and is supported through its side arms upon a cross rod 49. Rod 49 has secured 60 thereto an arm 50 (Fig. 2) provided with a handle 51 through which the cross member 48 may be rocked in a clockwise direction from the position in Fig. 1 and the roller 44 may be moved to one or another of the recesses 46. The free end of arm 65 50 is provided with a detenting pin 52 to retain the arm 50 and consequently cross frame 48 in any selected position. The purpose of shifting the point of connection is to increase or lessen the tension of springs 43 upon members 41 as desired and in accordance with the weight of impression or number of duplicate copies of the record to be printed upon.

Adjacent to member 41 is a type hammer 53 connected by a spring 54 to member 41, which spring serves to hold the left edge of the hammer

against a lateral extension 55 of member 41. If latch 38 is rocked clockwise, the hook 40 of member 41 will be released and spring 43 will thereupon urge member 41 in a clockwise direction, carrying with it the associated hammer 53 whose head 56 will thus be impelled against one of the type plungers 18 to urge the latter against printing ribbon 57 and platen 22. Head 56 is pivoted to the upper extremity of hammer 53 and held against a shoulder thereof by a light spring 58 10 to form a resilient connection between the head 56 and hammer 53. In the normal operation of cross member 33 the pivot rod 59 of latches 38 moves up and down with the cross member without disengaging the connection between latch 38 15 and hook 40 since as the pivot rod 59 moves upwardly, spring 39 will cause rocking of latch 38 in a counterclockwise direction to maintain its engagement with hook 40. Lying in the plane of latch 38 is a stopping pawl 60 normally held in 20 the position shown by a latch 61 connected by a call wire 62 to the armature 63 of the magnet 64. One terminal of the magnet has connection with an analyzing brush LB and the other, through usual circuit breaking devices, has connection 25 with one side of a source of current. As record cards are fed past the analyzing brushes a circuit through the magnet 64 will be completed at differential times depending upon the location of the perforation in the record card analyzed and at 30 the time of such analysis the correspondingly numbered type element will be approaching the printing position and latch 38 will be moving upwardly so that the sequence of operations will 35 be substantially as follows:

Assuming a perforation in, let us say, the "6" index point position of a column of the record card, upon the sensing of this position by the brush LB, a circuit will be completed to magnet 64 which will attract its armature 63, rocking 40 latch 61 out of engagement with the stopping pawl 60. The latter will thereupon rock clockwise and its toe will engage the right hand end of latch 38 establishing a fulcrum at the point of engagement so that as the cross member 33 45 rises, the left hand end of the latch 38 will do likewise and disengage itself from hook 40. Member 41 is thus released and under action of its spring 43 will impel hammer 53 and head 56 rapidly in a clockwise direction against the "6" 50 type element 18 which will at this time be in printing position opposite platen 22 and the impression will be taken from the type element without interrupting its upward movement. The flexible mounting of head 56 on arm 53 is 55 simply for the purposes of safety so that if for any reason arm 53 is retarded against return movement the striking end will not damage the type elements 18 by remaining in their path but will tilt upward as the crosshead 19 rises. It has 60 been found in practice that a clear print may be had with the head 56 integral with the arm 53. During the return or downward stroke of the type holder frame 11, 12 a cam 65 carried by shaft 28 will engage and rock the bell crank 66 connected through the link 67 to an arm 68 whose free end has pin and slot connection with a ball 69, and will cause counterclockwise rocking of the latter to restore the type hammers 53 and members 51 to latched position. At the same 70 time, a member 70 (Fig. 1) pivoted on rod 71 will be rocked in a counterclockwise direction by a cam 72 to rock ball 73 clockwise for the purpose of relatching stopping pawls 60 on latches 61.

As is customary in practice, zeros are perforated in fields of the record cards to fill out columnar positions to the left of the highest significant figure. However, it is not desired to print these extra zeros which are nevertheless sensed by the analyzing brushes and caused to complete circuits to printing magnets 64.

The energization of a magnet 64 in response to a zero perforation will not trip its latch 38 because at the time of tripping of stop 60 latch 38 will be raised beyond the engaging position and the toe of stop 60 will simply strike the end of the latch 38. Cam 35 is configured so that cross-head 33 does not descend after rising under the control of the "1" rise 37 but continues to rise to the level controlled by rise 37a (Fig. 6) thus not permitting latches 38 to re-descend into position to be tripped by stops 60.

Zero printing is therefore controlled through the higher order printing positions in the following manner: Each latch 38 is provided with a lateral extension 74 (see Fig. 5) which lies within the jaw of the bifurcated end of a member 75 which is pivoted at 76 to a fixed cross member. During the reciprocation of the cross frame 33 and the tripping of latches 38 there will be no engagement between extension 74 and member 75 (see Fig. 6). At the zero position, however, the greater rise 37a of cam 35 will cause a greater advance of pivot rod 59 and consequently a higher movement of the extensions 74 of latches 38 in those positions in which stop pawls 60 have previously been tripped in response to the analysis of a significant figure. The parts at such time will be in the position illustrated in Fig. 5 where pawl 60 is shown as having been tripped at some point previously and cross member 33 is at the upper extremity of its stroke causing additional rocking of latch 38 which in turn will engage and cause counterclockwise rocking of member 75 against the tension of its spring 77.

Each member 75 is provided with a lateral extension 78 (see Fig. 4) which extends over the upper edge of the next adjacent higher order member 75 so that rocking of any member 75 as in Fig. 5 will cause the next lower order member to be rocked likewise through the extension 78 of the latter member and it in turn will engage the lower edge of extension 74 of its latch 38 to disconnect the same from its member 41 whereupon the latter will cause the corresponding hammer to be impelled against the zero type plunger 18.

The members 75 are horizontally slidable and each is provided with a pivoted finger piece 79 through which the members 75 may be separately moved toward the left as viewed in Figs. 1 and 5. This will bring the extension 78 of the member 75 which has been moved toward the left over a lower portion of the upper edge of the next higher member 75 so that if such next higher member is rocked as explained, the motion will not be transmitted to the member which has been moved toward the left and the zero printing action will not take place. This is the so-called zero-splitting feature of tabulating printing mechanism.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It

is the intention therefore to be limited only as indicated by the scope of the following claims.

What is claimed is as follows:

1. In a printing mechanism, an invariably reciprocating type carrier, a printing hammer, impelling means for said hammer, means normally restraining said impelling means including a constantly rotating cam against operation, and means for releasing said restraining means during the reciprocation of said carrier to cause said impelling means to impel said hammer against said carrier. 5

2. In a printing mechanism, an invariably reciprocating type carrier, a printing hammer, impelling means for said hammer, an invariably reciprocating member provided with means for normally restraining said impelling means against operation, and means releasing said restraining means during the reciprocation of said carrier and said member to cause said impelling means to impel said hammer against said carrier. 10 20

3. In a printing mechanism, an invariably reciprocating type carrier, a printing hammer, a spring for urging said hammer against said carrier during its movement in one direction, a member and means for causing said member to reciprocate a number of times during a single reciprocation of said carrier, and means for selectively causing said member to cause said spring to actuate the hammer during one of the reciprocations of said member. 25 30

4. In a printing mechanism, an invariably reciprocating type carrier, a reciprocating member and means for causing said member to reciprocate more than once during a single reciprocation of said carrier, a printing hammer and means for causing said member to cause said hammer to be impelled against the carrier during any one of the reciprocations of said member. 40 35

5. In a printing mechanism, an invariably reciprocating type carrier, a spring-pressed printing hammer associated therewith, a reciprocating member and a latch carried thereby for holding said hammer against the action of its spring and means for causing said latch to release said hammer during the movement of said reciprocating member to cause said hammer to strike said carrier. 50 45

6. In a listing machine, a plurality of type members, means for continuously moving said members through a predetermined printing position, a spring-pressed printing hammer, a latch for said hammer, means for reciprocating said latch while in engagement with said hammer and means for causing rocking of said latch during its reciprocation to release said hammer for selectively printing from one of said type members while they are passing through printing position. 60 55

7. In a printing machine adapted to be controlled by record cards, sensing elements, type members, means for causing said members to move continuously toward a fixed printing position, a printing hammer, impelling means therefore, a latch for holding said hammer, a power device including a constantly rotating cam and means controlled by said sensing elements for causing said cam to operate said latch whereby said impelling means will move said hammer against said type members for selectively printing from said members while the latter are passing through said printing position. 70 65 75

8. In a printing machine, a constantly reciprocating type carrier, a plurality of type members carried thereby, a platen, a printing hammer adapted to strike any of said members
5 while the latter are passing said platen, impelling means for said hammer, a constantly re-

ciprocating actuator, and means carried by said actuator for causing said impelling means to operate said hammer.
